M. B. Munnell,
ATTORNEY*

UNITED STATES PATENT OFFICE.

DANIEL B. MEDANICH, OF BUECHEL, KENTUCKY.

VALVE-MOVEMENT.

1,326,208.

Specification of Letters Patent. Patented Dec. 30, 1919.

Application filed September 6, 1917. Serial No. 189,954.

To all whom it may concern:

Be it known that I, DANIEL B. MEDANICH, a citizen of the United States, residing at Buechel, in the county of Jefferson and 5 State of Kentucky, have invented certain new and useful Improvements in Valve-Movements, of which the following is a specification.

This invention relates to a valve movement adapted to be used in connection with internal combustion motors, and more particularly with the construction disclosed in my co-pending application Serial Number 74,697 filed Jan. 27, 1916, although it may 10 be found useful in other connections.

An object is to provide an improved method of operating a piston valve that shall be practical, efficient and noiseless.

With the foregoing and other objects in 20 view, the invention consists of the novel construction and arrangement of parts illustrated in the accompanying drawing, which forms a part of this specification, wherein is set forth an embodiment of the invention, 25 but it is to be understood that such changes and modifications may be resorted to as come within the scope of the appended claims.

Referring to the drawing, wherein similar reference characters designate like parts 30 in the several views, Figure 1, is a transverse sectional view of a motor embodying my invention: Fig. 2, a perspective view of the valve operating lever: Fig. 3, a perspective view of the auxiliary lever: Fig. 4, 35 a modified form of auxiliary lever, and Fig. 5, a transverse section of the valve operating cam.

Referring now in detail to the annexed drawing, a power cylinder —10— is mounted upon a suitable crank case —11—, within 40 which are movable respectively, a piston —12— and a crank —13—, the latter being connected to the piston by means of a connecting rod —14—, whereby motion is transmitted from the piston to the crank shaft. The motor illustrated is of a pattern popularly known as T head, exhaust and intake cylinders —15, 16— being disposed respectively, on opposite sides of the power 45 cylinder, and communicating therewith by means of ports —17, 18—. A water jacket —19— envelops the cylinders. The valve cylinders are open at the lower end to the atmosphere. Each of the valve cylinders is provided with an internal annular valve seat —20— (at the upper end thereof) 50 against which piston valves —21, 22— close. Valve rods —23— flexibly connected with the valves by suitable means, such as ball joints —24—, depend into position to be 55 actuated, to open the valve, through the medium of levers —25—, by cams —26— which are mounted on shafts —27—, said shafts receiving motion from the crank shaft by suitable means, such as belts —28—. 60 Springs —29— serve to return the valves to a closed position. A sleeve —30— is disposed in each valve cylinder and is retained therein by suitable means, such as plates —31— suitably secured to the lower end of 65 the valve cylinders, said plates also serve as supports for the springs 29. These sleeves extend from the lower end of the cylinder to within a spaced distance of the ports 17 and 18. By this arrangement a chamber 70 —32— is formed between the upper end of the sleeves and the valve seat 20 in which the heads —33— of the valves operate. The body —34— of the valve is of reduced diameter to fit the bore of the sleeves. An advantage of this construction is that in case 75 of wear, new sleeves may be inserted, instead of having to re-bore the cylinder. The length of the chamber 32 is such that when the heads of the valves have cleared the 80 ports 17 and 18, there will be a space between the under side of the heads and the upper ends of the sleeves. It is to be observed that the gases from the power cylinder 85 find their way all around the body of the valves, below the heads, subjecting them to equal pressure on all sides, avoiding wear and friction due to side pressure, and also serve as a cushion in the opening movement. The inlet valve cylinder communicates at 90 its upper end with a transverse passage —35— which extends across the head of the engine, and at its outer end is provided with means such as a flange —36— for the attachment of a conduit, which leads to a suitable 95 source of fuel supply, this passage divides, and passes around a well —37— within which is positioned a spark plug —38—. An exhaust tube —39— passes through the intake passage 35, the arrangement being 100 such that the incoming fuel impinges upon the tube and is heated by contact therewith. One limb —40— of the operating lever 25 has an enlarged head —41— which is provided with a slot —42— through which the 105 valve rod 23 passes. Suitable means such as a nut —43—, is engaged with the valve

rod, below the head, and upon this the lever bears. The inner end of the limb 40 is bifurcated and the bifurcations —44— are provided with bearings —45— which embrace the shaft 27. Legs —46—, which depend from the bifurcations, bear on their lower ends, oppositely disposed alined rollers —47—. On each face of the cam 26, spaced from and following the periphery thereof, is 10 a groove —48— which is adapted to receive the rollers 47. An auxiliary lever —49— is pivoted on the shaft 27, between the bifurcations of the lever 25, a depending limb —50— of this lever has a roller —51— 15 adapted to bear on the periphery of the cam, the other limb —52— extends along with the limb 40 of the main lever 25, and suitable means are provided to co-act with the respective limbs and cause the roller 51 to 20 hug the periphery of the cam. Such means may be a threaded post —53— extended from the arm of the main lever through a perforation —54— in the arm of the auxiliary lever and carrying a thumb nut —55— 25 which may be brought to bear against the auxiliary arm and cause the roller to bear unyieldingly against the cam. Or resilient means, such as a spring —56— may be positioned between the two levers, in which case 30 the roller 51 will be held against the cam with a yielding pressure. It will be observed that with the construction described, there will be no lost motion between the rollers and the cam and that any wear, of either, 35 will be taken up. It is also to be observed that as the piston rod is free to move downward through the slot 42 in the head 41 of the operating lever, that, in the case of the exhaust valve, as soon as the valve is moved 40 clear of its seat through the action of the lever, the head of the valve will be subjected

to the pressure of the gases from the power cylinder, and the valve will be forced open thereby with a movement more rapid than, and independent of that of the operating 45 lever, which later will catch up with and control the closing movement of the valve.

Having thus described my invention so that any one skilled in the art pertaining thereto, may make and use the same, I claim: 50

1. In a motor as characterized, a valve, a rod connected therewith, means for operating said valve, comprising an angular lever, one arm of which is operatively connected with said rod, the other arm thereof being 55 bifurcated, a cam having grooves on both faces positioned between said bifurcations, pins extended from the bifurcations and seated in said cam grooves, an auxiliary lever associated with the first named lever 60 and adapted to bear upon the periphery of the cam, and a resilient element disposed between said levers and adapted to cause contact with the cam surfaces.

2. In a valve movement, a valve, a rod 65 connected therewith, a cam shaft, a cam having grooves on both faces mounted thereon, a parallel shaft, an angular lever mounted thereon, one arm whereof is operatively connected with said rod, said lever being bifurcated for a portion of its length and the shaft bearings being in the furcations, pins 70 extended from the furcations and received in said grooves, a second angular lever mounted on said parallel shaft between the furcations of the first mentioned lever and having a roller on one end adapted to bear on the periphery of the cam, and a resilient element 75 positioned between the extended arms of the two levers.

DANIEL B. MEDANICH.
